HYPODERMIC SYRINGE

Niels Bjorn Jorgensen, Los Angeles, Calif.

Application August 9, 1952, Serial No. 303,514

2 Claims. (Cl. 128—218)

1 This invention relates to hypodermic syringes of the type in which the barrel of a medicine ampule becomes the cylinder of the syringe and in which a stopper of yieldable material such as rubber, closing one end of the ampule, becomes the piston of the syringe. The general object of the invention is to provide for such a syringe, an improved stopper having the dual function of (a) ejecting the contents of the ampule in its normal functioning; and (b) developing a limited amount of suction for withdrawal of fluid from a patient's body into the syringe, to test whether a blood vessel has been punctured. In general, the present invention constitutes an improvement upon those covered by my two earlier Patents No. 2,526,365, issued October 17, 1950, and No. 2,554,744, issued May 29, 1951. The stoppers of those patents, insofar as they are adapted to be used with a standard syringe plunger, are characterized by having a generally cup shaped body portion of resilient material such as soft rubber, the end wall thereof being in the form of a relatively thin diaphragm, and means is provided for stretching the diaphragm into the cavity of the stopper without moving the stopper in the cylinder, so as to expel some of the liquid from the cavity, the diaphragm, when released, returning to its original position and thereby exerting a suction effect.

As in the device of my prior patents, the present invention provides a one piece, generally cup shaped stopper or piston having at one end means adapted, while the body of the stopper hugs the wall of the cylinder and remains fixed therein, to respond to the pressure of the syringe plunger in a manner to expel a portion of the fluid from the interior of the stopper; said means having the characteristic of returning to its original form when the plunger pressure is released, thereby exerting a suction effect for drawing back into the syringe a quantity of fluid equal to that expelled from the stopper on the forward movement of the piston; and the stopper being further adapted, after the initial stroke of the plunger (which provides for the suction effect) has been completed, to receive the plunger pressure in a manner to be driven forwardly in the cylinder for the normal ejection of the contents from the syringe.

The primary object of the present invention is to provide, in a stopper having these general characteristics and adapted for use in a standard syringe, an improvement whereby the volume of fluid that may be ejected from and drawn back into the stopper, may be greatly increased

5 without unduly straining the resilient material of the stopper, or incurring any likelihood of the stopper slipping against the cylinder wall during the initial stage of partial ejection and suction action.

Other objects will become apparent in the ensuing specifications and appended drawings in which:

Fig. 1 is a sectional view of a portion of syringe embodying the invention;

Fig. 2 is a side view of the stopper;

Fig. 3 is a sectional view illustrating the end of the initial compression stage of operation; and

Fig. 4 is a sectional view of a modified form of the stopper.

Referring now to the drawings in detail, I have illustrated my invention in connection with a syringe embodying a holder, indicated generally at 6, and a medicine ampule, indicated generally at 7. The holder 6 includes a barrel 8 having one end closed by a narrow neck in which is mounted a conventional hollow needle (not shown). The other end of the holder is open to receive the ampule 7. To the open end of the barrel 8 is hinged, upon trunnion 9, a yoke 10 having laterally projecting finger grips 11 and a bearing 12 in which is slidably mounted a plunger 13. Ampule 7 includes a glass cylinder 14 having an open end to receive plunger 13 and having at its other end a stopper adapted to be pierced by the inner end of the needle mounted in the neck of the holder 6. These parts being well known, are not illustrated herein, and reference is made to my prior patents referred to above, for a more complete disclosure of these conventional elements.

For the open end of the ampule cylinder 14, the invention provides a hollow stopper or piston, indicated generally at 15, the stopper 15 including a main body portion in the form of a relatively thick cylindrical skirt 16 having annular sealing grooves 17 and 18 in axially spaced relation therein, for increased efficiency of sealing against the escape of fluid past the stopper. The outer end of the stopper is formed with a bulb 19 having a relatively thin, cylindrical annular wall portion 20 and a crown portion 21 which may, as shown, be relatively flat to fit the end of plunger 13. The thickness of annular wall 20 is only a fraction that of skirt 16 (e. g. from one third to one fourth). Accordingly, where wall portion 20 joins skirt 16, there is formed a shoulder 22. Shoulder 22 is an external shoulder projecting radially outwardly from lateral wall 20.

3

In the form of the invention shown in Fig. 1, the lateral wall 20 of bulb 19 has its inner wall aligned with and forming a continuation of the wall of cavity 23 in sleeve 16.

In the modified form of the invention shown in Fig. 4, bulb 19a has an outer diameter equal to or less than the diameter of cavity 23.

In the operation of the invention, after the ampule has been inserted into the syringe and the yoke 10 moved to an operative position with plunger 13 in alignment with the axis of barrel 8, the syringe is immediately ready for use. After the needle has been inserted into a patient's body, if the operator desires to test whether a blood vessel has been pierced, he carefully presses the plunger 13 inwardly, collapsing bulb 19 against shoulder 22. The starting position is shown in Fig. 1 and the end of this initial stage of operation is shown in Fig. 3. Thereupon, by releasing the pressure against plunger 13, the bulb 19, being of resilient material, will regain its original form shown in Fig. 1 and in doing so will draw back into the syringe the amount of fluid that was initially expelled therefrom. The volume of bulb 19 is regulated to provide for withdrawing a sufficient amount of fluid to bring into the transparent cylinder 14 enough blood to make the same visible to the operator, in the event a vessel has been punctured.

The advantage of the invention over earlier devices of this type that are designed for use in a standard syringe, resides in the fact that the extremely thin walled bulb 19 may be collapsed with only a very slight amount of pressure on plunger 13, much less than would be required to stretch a diaphragm of the same thickness into the cavity 23. A further advantage resides in the fact that the bulb may be made of any desired depth to provide the required volume of initial ejection and withdrawal, without increasing the force that must be applied thereto in order to fully collapse the bulb. Accordingly, the likelihood of the skirt 16 slipping in the cylinder 14 under the load applied to the initial ejection and withdrawal device (bulb 19) is eliminated, and it becomes possible to provide an even looser fit of the skirt 16 in the cylinder 14, and consequently a smoother and easier piston action when the stopper is pushed forwardly in the final syringe action.

After the testing operation has been completed, the operator again advances the plunger 13 until the bulb 19 is fully collapsed against shoulder 22. Further movement of plunger 13 will then be transmitted through shoulder 22 to skirt 16, since the inner end of plunger 13 is of larger diameter than the diameter of cavity 23.

The operation in the form shown in Fig. 4 is the same as in the other form of the invention, with the exception that bulb 19a, being of an outer diameter equal to or less than the diameter of cavity 23, is adapted to enter cavity 23 until it is completely received therein, as indicated in dotted lines in Fig. 4, and plunger 13 is thereby permitted to engage directly with shoulder 22, as also indicated in dotted lines.

It will be understood that the stopper of my invention is constructed from soft rubber or equivalent material, including some of the thermoplastic resin (such as the vinyl plastic).

I claim:

1. A component for a hypodermic syringe having a plunger, a piston, and a cylinder in which

4

said piston is operable: said component consisting in a medicant ampule including a barrel adapted to function as said cylinder and a stopper in one end of said barrel adapted to function as said piston, said stopper being integrally molded of a resilient material having the characteristics of soft rubber, and including an annular relatively thick walled skirt received in and in sealing engagement with the wall of said barrel, said skirt having an axial cavity, open at its inner end, and a bulb on the outer end of said skirt, having a cavity formed as a continuation of said skirt cavity, the outer end of said skirt defining, at the base of said bulb, an annular external shoulder extending from said bulb radially outwardly to the lateral face of said skirt, said bulb being adapted to be engaged by the inner end of said plunger and collapsed in an initial range of plunger movement, while the skirt remains fixed in the cylinder, and being form regaining after plunger pressure is released, whereby to effect a suction for drawing back into the syringe a quantity of fluid equal to that discharged therefrom in the collapsing of the bulb, said bulb having a wall thickness only a fraction of that of said skirt, having an outer diameter equal to or less than the diameter of said skirt cavity, and being adapted, during said collapsing, to be displaced into said skirt cavity so that said plunger may directly engage said annular shoulder for advancing said stopper in said barrel.

2. A component for a hypodermic syringe having a plunger, a piston, and a cylinder in which said piston is operable: said component consisting in a medicant ampule including a barrel adapted to function as said cylinder and a stopper in one end of said barrel adapted to function as said piston, said stopper being integrally molded of a resilient material having the characteristics of soft rubber, and including an annular relatively thick walled skirt received in and in sealing engagement with the wall of said barrel, said skirt having an axial cavity, open at its inner end, and a bulb on the outer end of said skirt, having a cavity formed as a continuation of said skirt cavity, the outer end of said skirt defining, at the base of said bulb, an annular external shoulder extending from said bulb radially outwardly to the lateral face of said skirt, said bulb being adapted to be engaged by the inner end of said plunger and collapsed in an initial range of plunger movement, while the skirt remains fixed in the cylinder, and being form regaining after plunger pressure is released, whereby to effect a suction for drawing back into the syringe a quantity of fluid equal to that discharged therefrom in the collapsing of the bulb, said bulb having a wall thickness only a fraction of that of said skirt, having an outer diameter substantially the same as the diameter of said skirt cavity, and being adapted, during said collapsing, to be displaced into said skirt cavity so that said plunger may directly engage said annular shoulder for advancing said stopper in said barrel.

NIELS BJORN JORGENSEN.
